T. H. ROBINSON

FUEL SAVING DEVICE

Filed April 10, 1926

FIG. 3. *Inventor*
Thomas H. Robinson

by J. C. Hartshough & Co
Atlys.

UNITED STATES PATENT OFFICE.

THOMAS HARTLEY ROBINSON, OF STRATFORD, ONTARIO, CANADA.

FUEL-SAVING DEVICE.

Application filed April 10, 1926. Serial No. 101,181.

My invention relates to improvements in fuel saving devices, and the object of the invention is to devise simple means for evenly superheating air to discharge it over the incandescent fuel bed to produce secondary combustion, and it consists essentially of the arrangement and construction of parts as hereinafter more particularly explained.

Fig. 1 is a sectional plan view taken 10 through a furnace fire pot showing my device in position.

Fig. 2 is a vertical section through Figure 1 showing my device in elevation.

Fig. 3 is an enlarged sectional plan view 15 through my device.

Fig. 4 is a front elevation of my device.

In the drawing like characters of reference indicate corresponding parts in each figure.

1 indicates a furnace fire pot provided 20 with the usual fire door 2 provided with an air damper 3 through which a controlled supply of air is passed in the usual manner into the interior of the fire pot. 6 is a stem 25 like member provided with an end flange 7 which is bolted to the fire door 2. The outer end of the stem 6 is provided with an opening 8 which registers with the air opening formed in the fire door, the sides of such 30 opening preferably converging as indicated at 8^x and 8° to form a narrow mouth 9. 10 is a screw which extends through the top of the stem 6 extending vertically of the mouth 9 so as to control the size of such 35 mouth and consequently the supply of air into the body of the stem. 10 and 11 are zigzag passageways, the arms of which are in longitudinal alignment one with the other to form mouths 12, 13, 14 and 15. The air 40 is finally discharged through a mouth 16 at the inner end of the stem.

When the device is placed in position within the furnace as shown in Figures 1 and 2 and the damper 3 is opened to permit 45 the passage of air therethrough such air passes through the mouth 9 part flowing in one direction and part flowing in the opposite direction as indicated by arrow, such air streams meeting and crossing each other 50 as also indicated by arrow at the mouth 12

so that as the air is gradually heated it is mixed and thereby insuring that the air is raised to an even temperature as it passes longitudinally of the stem, the streams of air crossing and recrossing at the mouths 55 13, 14 and 15 to be finally discharged over the fire bed at 16. Such superheated air mixes with the products of combustion to produce a secondary combustion and thereby utilize gases for heating purposes which 60 ordinarily pass off.

From this description it will be seen that I have devised a very simple device whereby air may be evenly and thoroughly superheated and discharged in a superheated condition over the fire bed to unite with the products of combustion.

What I claim as my invention is:

1. In a furnace, the combination with the fire door having an air inlet damper, of a 70 hollow stem extending from the inlet of the damper and having a plurality of passages extending therethrough so arranged as to divide the flow of air into a plurality of streams which cross and recross each other 75 at spaced intervals apart during its passage towards the discharged end of the stem.

2. In a furnace, the combination with the fire door having an air inlet damper, of a hollow stem extending from the inlet of the 80 damper and having a plurality of passages extending therethrough so arranged as to divide the flow of air into a plurality of streams which cross and recross each other at spaced intervals apart during its passage 85 towards the discharged end of the stem, and means for controlling the flow of air into such passages.

3. The combination with a furnace fire pot and fire door having an air inlet damper therein, of a hollow stem supported by the fire door so as to receive air from the damper and having passages formed therein arranged in diamond shaped formation to divide the flow of air into streams which cross and recross at spaced apart intervals during its passage from one end of the stem 90 to the other.

THOMAS HARTLEY ROBINSON.
